UNITED STATES PATENT OFFICE

HUGH ALBERT BUCCINI, OF PORT JERVIS, AND STANLEY H. BARNES, OF NEW ROCHELLE, NEW YORK, ASSIGNORS TO GLEASON-TIEBOUT GLASS COMPANY, OF BROOKLYN, NEW YORK, A CORPORATION OF NEW YORK

DESIGN FOR A SHADE OR SIMILAR ARTICLE

Application filed October 8, 1931. Serial No. 41,344. Term of patent 3½ years.

To all whom it may concern:

Be it known that we, HUGH ALBERT BUCCINI and STANLEY H. BARNES, citizens of the United States of America, and residents, respectively, of Port Jervis, county of Orange, State of New York, and New Rochelle, county of Westchester, and State of New York, have invented a new, original, and ornamental Design for a Shade or Similar Article, of which the following is a specification, reference being had to the accompanying drawing, forming a part thereof.

In the drawing:

It is understood that the half of the design shown in dot and dash outline is to be similarly ornamented as the half fully illustrated.

We claim:

The ornamental design for a shade or similar article, substantially as shown.

Signed at Port Jervis, in the county of Orange and State of New York, this 2nd day of October, 1931.

HUGH ALBERT BUCCINI.

Signed at Brooklyn, in the county of Kings and State of New York, this 8th day of August, 1931.

STANLEY H. BARNES.
